CONVERTIBLE TOP FOR FIRE ENGINES

Donald V. Walthers, Sr., 16366 E. Bridger,
Covina, Calif. 91722

Filed Mar. 28, 1966, Ser. No. 1,665

Term of patent 14 years

(Cl. D14—27)

FIGURE 1 is a perspective view of a convertible top for fire engines, showing my new design;

FIGURE 2 is a top view thereof;

FIGURE 3 is a side elevational view thereof;

FIGURE 4 is a rear end view thereof; and

FIGURE 5 is a front end view thereof.

The broken lines are for illustrative purposes only.

I claim:

The ornamental design for a convertible top for fire engines, as shown and described.
